CLAIM

The ornamental design for a weight modification clamp, as shown and described.

DESCRIPTION

FIG. 1 is a perspective view of a weight modification clamp according to the present invention and with the clamp in a closed position;

FIG. 2 is a perspective view of the weight modification clamp of FIG. 1 and with the clamp in an open position;
FIG. 3 is a left side view of the weight modification clamp of FIG. 1;

FIG. 4 is a right side view of the weight modification clamp of FIG. 1;

FIG. 5 is a rear view of the weight modification clamp of FIG. 1;

FIG. 6 is a front view of the weight modification clamp of FIG. 1;

FIG. 7 is a top view of the weight modification clamp of FIG. 1;

FIG. 8 is a bottom view of the weight modification clamp of FIG. 1; and,

FIG. 9 is another perspective view of the weight modification clamp of FIG. 1.

The broken lines shown in FIG. 9 are for the purpose of illustrating the environment in which the weight modification clamp is associated and form no part of the claimed design.

The jagged line in FIG. 9 represents the bounds of the environment in which the weight modification clamp is associated and forms no part of the claimed design.

1 Claim, 5 Drawing Sheets
